UNITED STATES PATENT OFFICE

130,936

DESIGN FOR A COMBINED TOOTHBRUSH RACK AND DENTIFRICE CONTAINER

Jesse Marion Casey, Centralia, Ill.

Application August 11, 1941, Serial No. 102,788

Term of patent 3½ years

To all whom it may concern:

Be it known that I, Jesse Marion Casey, a citizen of the United States, residing at Centralia, in the county of Marion and State of Illinois, have invented a new, original, and ornamental Design for a Combined Toothbrush Rack and Dentifrice Container, of which the following is a specification, reference being had to the accompanying drawing, forming a part thereof.

I claim:

The ornamental design for a combined toothbrush rack and dentifrice container substantially as shown.

JESSE MARION CASEY.
